UNITED STATES PATENT OFFICE

121,185

DESIGN FOR AN AUTOMOTIVE VEHICLE

Herman Z. Cutler, Camden, N. J.

Application September 30, 1938, Serial No. 80,158

Term of patent 7 years

To all whom it may concern:

Be it known that I, Herman Z. Cutler, a citizen of the United States and a resident of Camden, in the county of Camden and State of New Jersey, have invented a new, original, and ornamental Design for an Automotive Vehicle, of which the following is a specification, reference being had to the accompanying drawings forming a part thereof, and in which

Figure 1 is a top plan view of an automotive vehicle embodying my new design,

Figure 2 is a side elevational view thereof,
Figure 3 is a front elevational view thereof,
and

Figure 4 is a rear elevational view thereof.

I claim:

The ornamental design for an automotive vehicle, substantially as shown.

HERMAN Z. CUTLER.
